Des. 205,903
Patented Oct. 4, 1966

205,903

ELECTRIC IRON

Eric J. Marshall, Farnborough Park, Edward G. Grinyer, Pinner, and Peter J. Barber, Epsom, England, assignors to The Hoover Company, North Canton, Ohio, a corporation of Ohio

Filed May 11, 1965, Ser. No. 85,224

Claims priority, application Great Britain Nov. 23, 1964

Term of patent 14 years

(Cl. D49—6)

FIGURE 1 is a perspective view of an electric iron embodying our new design;

FIGURE 2 is a rear elevational view thereof;

FIGURE 3 is a top plan view thereof;

FIGURE 4 is a front elevational view thereof, and

FIGURE 5 is a side elevational view thereof.

The dominant features of our design reside in the portions shown in full lines.

We claim:

The ornamental design for an electric iron, substantially as shown and described.
